UNITED STATES PATENT OFFICE.

PETER SAVAGE, OF ADAMS, MASSACHUSETTS.

IMPROVEMENT IN DRILL-HOLDERS FOR ROCK-DRILLING MACHINES.

Specification forming part of Letters Patent No. 130,246, dated August 6, 1872.

SPECIFICATION.

To all whom it may concern:

Be it known that I, PETER SAVAGE, of Adams, in the county of Berkshire and State of Massachusetts, have invented certain new and useful Improvements in Drill-Chucks; and I do hereby declare that the following is a full, clear, and exact description thereof, reference being had to the accompanying drawing and to the letters of reference marked thereon, which form a part of this specification, in which—

Figure 1 represents a perspective view of my drill-chuck, and Fig. 2 is a detached view of the same.

The object of my invention is to hold the drills of rock-drilling machines, or to be used as an ordinary chuck; and the nature of it consists in the construction and arrangement of a "drill-chuck," as will be hereinafter more fully set forth.

In order to enable others skilled in the art to which my invention appertains to make and use the same, I will now proceed to describe its construction and operation.

A represents the head of my "drill-chuck," to be constructed of one solid piece of metal. Through this head is bored a hole for the re-

ception of the drill B. Into recesses or cavities *a a* on the sides of the head are inserted two straps, C C, Fig. 1, upon the inner sides of which are lugs *b b*, provided with V-shaped grooves *c c*, Fig. 2, which clasp the drill and hold it firmly in its place. These straps are fastened to the head by means of bolts D D and nuts *d d*, as fully shown in Fig. 1.

It will be observed that by constructing the head of one solid piece it is not subject to any breakage caused by the bearing upon the drill.

Having thus fully described my invention, what I claim as new, and desire to secure by Letters Patent, is—

1. The straps C C formed with lugs *b b*, said lugs being provided with V-shaped grooves *c c*, substantially as and for the purpose set forth.

2. The combination of the straps C C, head A, bolts D D, and nuts *d d*, all constructed and arranged substantially as described.

In testimony that I claim the foregoing as my own I hereunto affix my signature in presence of two witnesses.

Witnesses: PETER SAVAGE.
